INVENTOR
BY Victor G. Eams
ATTORNEY

UNITED STATES PATENT OFFICE.

ROBERT WIRZ, OF MILWAUKEE, WISCONSIN.

NECKTIE HOLDER.

Application filed December 1, 1922, Serial No. 604,328. Renewed August 21, 1924.

To all whom it may concern:

Be it known that I, ROBERT WIRZ, a citizen of the United States, residing at Milwaukee, in the county of Milwaukee and 5 State of Wisconsin, have invented new and useful Improvements in Necktie Holders, of which the following is a specification.

The object of my said invention is the provision of a necktie holder of simple and 10 strong construction adapted more particularly for use in conjunction with "four in hand" neckties, and susceptible of association with low or high collars and in such manner that the tie can be readily adjusted 15 relative to the holder so that when one portion of the tie is soiled or worn another portion of the tie can be positioned for display.

To the attainment of the foregoing, the 20 invention consists in the improvement as hereinafter described and definitely claimed.

In the accompanying drawings, forming 25 part of this specification:—

Figure 1 is a perspective showing my novel 30 holder as properly arranged relative to a turned down collar and a four in hand necktie.

Figure 2 is a rear elevation showing the 35 holder and tie in combination.

Figure 3 is a perspective of my novel holder per se.

Similar numerals of reference designate 40 corresponding parts in all of the views of the drawings.

The major portion of my novel holder is 45 formed of a single piece of wire possessed of more or less resiliency, and a central body of solder or equivalent material through the medium of which the central portions of the piece of wire are joined together in fixed relation. The major portion of wire comprises a top wall 1, loops 2 and lower bars 3, each of which serves in connection with the part of the top bar above it to form one of the loops 2. The bar 1 is dished as illustrated 50 to give the holder a general concavo-convex configuration with the concave uppermost, and the bars 3 are merged at their inner ends into loops 4 which, in turn, are merged into pendent yoke portions 5. The body of 55 solder or equivalent material is designated by 6 and serves to fixedly join the bight or center portion of the bar 1 and the loops 4 so that the said loops 4 are strongly fixed with respect to the yoke portions 5 and the bight or center portion of the bar 1. The

yoke formed in the manner stated by the body 6 and the yoke portions 5 is adapted to straddle the shank of a collar button back of the head thereof so as to securely though detachably secure the holder and the tie associated therewith in proper position for wear relative to the collar button and the collar connected to the collar button as shown in Figures 1 and 2.

By particular reference to Figures 1 and 2 it will be noted that the collar is designated by 7 and the necktie is designated by 8. It will also be noted that the necktie is so arranged that it has the foremost crosswise loop 9, back loops 10 and 11 and pendent end portions 12 and 13, the loops 10 and 11 extending forwardly over the holder, and the end portions 12 and 13 being carried downwardly in front of the holder and through the crosswise loop 9. From this it follows that the necktie may be expeditiously and easily adjusted as to length or lengthwise relative to the holder without disassociation of the holder and necktie so that when a portion of the necktie has become soiled or worn a fresh portion of the tie may be displayed for use and wear. Manifestly in virtue of this, the usefulness and dressy appearance of the tie will be prolonged for an indefinite period.

My invention contemplates marketing the holder per se as an article of manufacture and also contemplates the marketing as a new device of personal wear the holder in combination with the necktie arranged relative to the holder so that the purchaser of the device is made aware of the manner in which the necktie and holder are combined and is made fully appreciative at the outset of the adaptability of the necktie to be adjusted in the manner and for the purpose described relative to the holder.

Manifestly my novel holder is adapted to be manufactured at small cost so that it is entirely feasible when deemed expedient to sell the holder with a necktie for a price but little greater than the selling price of the same necktie without a holder.

I have entered into a detailed description of the construction and relative arrangement of the parts embraced in the present and preferred embodiment of my invention in order to impart a full, clear and exact understanding of the said embodiment. I do not desire, however, to be understood as con-

fining myself to the specific construction and relative arrangement of parts inasmuch as in the future practice of the invention various changes and modifications may be made 5 such as fall within the scope of my invention as defined in my appended claims.

Having described my invention, what I claim and desire to secure by Letters Patent, is:—

- 10 1. As a new article of manufacture, a necktie holder comprising a major portion of wire, including a dished top bar, lower bars joined through bights to the ends of the top bar and extending inwardly from 15 said bights to points below and adjacent to the central portion of the top bar and having loops at their inner ends, and pendent yoke portions into which the said loops merge, and a central solid body of solder through the medium of which the latter

loops and the central portion of the top bar are fixedly connected together.

2. A necktie holder having a dished top bar and also bars joined through bights to the ends of the top bar, and loops at the inner ends of the lower bars and pendent yoke portions extending from said loops and also having a body through the medium of which the latter loops and the central portion of the top bar are fixedly connected together, 30 in combination with a necktie having a crosswise loop in front of the central portion of the holder and also having loops extending forwardly over the holder and pendent portions carried by said loops and extending downwardly through the first-named necktie loop. 35

In testimony whereof I affix my signature.

ROBERT WIRZ.
